Inventor.

UNITED STATES PATENT OFFICE

HIRAM H. FOWLER, OF MEADVILLE, PENNSYLVANIA.

SWING.

SPECIFICATION forming part of Letters Patent No. 367,204, dated July 26, 1887.

Application filed November 23, 1886. Serial No. 219,624. (No model.)

To all whom it may concern:

Be it known that I, HIRAM H. FOWLER, a citizen of the United States, residing at Meadville, in the county of Crawford and State of Pennsylvania, have invented certain new and useful Improvements in Swings; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 The special object of the invention is to construct a swing in such manner that it may be worked with the hands with ease and safety, either sitting or standing on the footrests.

Figure 1 of the drawings is a front view in 20 elevation; Fig. 2, a vertical section on line x of Fig. 1, and Fig. 3 a detail view.

In the drawings, A represents the supporting-frame, and B the pivoted seat-frame, both of which are substantially the same as shown 25 in my application No. 210,895, filed August 14, 1886.

C is the seat, which may be rigid or pivoted, and of which there may be two, placed so as to have a common back, or one only.

30 D are arms pivoted at their rear to the swinging bars B' B', and each connected at its front end with the diagonally-opposite ends a of the supporting-frame by the ropes E E, which may be fastened in the rings a'. The 35 arms D D are connected at their front ends by the bar D', which forms a handle, which is grasped by the swinger; so as to propel himself back and forth by a union of his muscular power and his weight. He is thus able to 40 graduate his movements with much less danger, with more accuracy, and with much less fatigue, while the muscles of the whole body are more or less exercised and the strain is not thrown so entirely upon the legs and the 45 muscles of the lower part of the body as when a treadle is employed.

The arms D are provided with end slots,

d d, made horizontally, and vertical holes d', by which the handle D' may be adjusted outwardly to a greater or less extent to suit a 50 different length of arm in the swingers, the handle D' being made with holes d', and being held to the arms by pins or bolts passing through said holes. I preferably use eyebolts F, to which the ropes E E are secured adjustably by means of the hooks and eyes f f', so as to correspond with the distance out to which the handle D' is adjusted.

G G are foot-rests pivoted at the rear ends to the pivoted bars B', and connected with the 60 brace-bars B' by buckle-straps g g, so that they may be raised to or lowered from the seats, according to the length of leg of the swinger.

The swing as thus constructed is found in practice to operate with great facility, with 65 wonderfully little physical exertion, and with scarcely any liability to accident of any kind. Children may be safely trusted to amuse and exercise themselves without fear that they will fall out or hurt themselves in any way. 70

Having thus described all that is necessary to a full understanding of my invention, what I claim as new, and desire to protect by Letters Patent, is—

1. In a swing, the combination, with the 75 frame A, ropes E, and pivoted bars B' B', of the arms D D, pivoted to said bars above the seat at their rear ends and provided in front with the handle D', as shown, and for the purpose described.

2. The combination, with the frame A, swing-bars B', and ropes E, having the hooks and eyes f f', of the arms D D, slotted at their front ends and pivoted at their rear ends to the swing-bars B', the connecting handle-piece 85 D', held adjustably in said slots by the eyebolts F, whereby said handle-piece and ropes may be correspondingly adjusted, as described.

In testimony whereof I affix my signature in presence of two witnesses.

HIRAM H. FOWLER.

Witnesses:

A. RUPPERT,
THOMAS P. SIMPSON.
